(57) **CLAIM**

The ornamental design for a styling comb, as shown and described.

DESCRIPTION

FIG. 1 is a perspective view of the styling comb;
 FIG. 2 is a left side elevation view thereof;
 FIG. 3 is a right side elevation view thereof;
 FIG. 4 is a front elevation view thereof;
 FIG. 5 is a rear elevation view thereof;
 FIG. 6 is a top plan view thereof;
 FIG. 7 is a bottom plan view thereof;
 FIG. 8 is a left side elevation view of the styling comb without broken lines; and,
 FIG. 9 is a left side view of the styling comb with additional broken lines.

The other views of the styling comb as shown in FIGS. 8 and 9 correspond to FIGS. 3-7, incorporated by reference, with corresponding solid or broken line variations.

1 Claim, 9 Drawing Sheets(56)
